UNITED STATES PATENT OFFICE.

EARL B. LEAR, OF PHILLIPSBURG, NEW JERSEY, ASSIGNOR TO INGERSOLL-RAND COMPANY, OF JERSEY CITY, NEW JERSEY, A CORPORATION OF NEW JERSEY.

VALVE FOR ROCK DRILLS.

Application filed August 30, 1927. Serial No. 216,403.

This invention relates to rock drills, but more particularly to a distributing valve for fluid actuated rock drills of the hammer type.

- The objects of the invention are to effect a rapid distribution of the pressure fluid to the cylinder, to produce a rugged valve capable of withstanding the severe usage to which valves of this type are subjected, and to obtain a positive action of the valve.
- 10 Other objects will be pointed out hereinafter, and to all of these ends the invention consists of the combination of elements and arrangement of parts having the general mode of operation substantially as hereinabove described and claimed and illustrated in the accompanying drawings, in which—

Figure 1 is a longitudinal elevation in section of so much of a rock drill as will serve to illustrate the invention, showing the valve 20 in one of its extreme positions, and

Figure 2 is a view similar to Figure 1, showing the valve in its other extreme position.

Referring more particularly to the drawings, A designates a cylinder having a free exhaust port B controlled by a piston C reciprocable in the cylinder A. The ends of the cylinder A may be sealed in any suitable manner. In the drawings, a front cylinder 25 washer D serves this function at the front end of the cylinder A and in the rearward end of the cylinder is disposed a back cylinder washer E bored in this instance to receive a rifle bar F which extends into and engages the piston C in a well known manner for imparting rotary movement to the piston.

In accordance with the present invention, the cylinder A is provided with a valve chest G having a cylindrical bore H of substantially 30 uniform diameter throughout its length. In the ends of the bore H are disposed plugs J and K held in operative position by means of bolts L. At the outer ends of the plugs J and K are formed flanges O which bear 35 against the ends of the valve chest G to limit the distance which the said plugs J and K may extend into said valve chest. The inner or adjacent ends of the plugs J and K in this instance are suitably spaced with respect to 40 each other to permit the passage of pressure fluid therebetween into the valve chamber P.

The valve chamber P in this instance comprises an enlarged central portion Q and reduced end portions R and S formed in the 45 plugs J and K respectively.

From the end portion R of the valve chamber extends an inlet passage T leading to the rearward end of the cylinder for conveying pressure fluid thereto to actuate the piston C in a forwardly direction. Similarly, from 60 the rearward end portion S of the valve chamber P leads an inlet passage U which terminates at its outlet end in the front end of the cylinder for conveying pressure fluid thereto to impel the piston C rearwardly. 65

Disposed within the valve chamber P is a distributing valve V having end projections W and X guided by the reduced end portions R and S respectively of the valve chamber P. The ends Y and Z of the projections W 70 and X constitute holding surfaces against which pressure fluid in passing to the ends of the cylinder may act for holding the valve in its extreme positions.

Intermediate the ends of the valve V is 75 formed an external flange b of substantially the same diameter as the central portion Q of the valve chamber. The front and rearward ends of the flange b constitute actuating surfaces c and d against which pressure fluid 80 admitted through kicker passages e and f may act for actuating the valve. As will be observed the kicker passage e leads from a point in the cylinder forwardly of the free exhaust port B to the front end of the enlarged portion Q of the valve chamber and the kicker passage f leads from a point rearwardly of the exhaust port B to the rearward end of the enlarged portion Q of the valve chamber. The kicker passages e and 85 f are controlled entirely by the piston C 90 whereby they are uncovered at the proper period in the cycle of operations for admitting pressure fluid into the valve chamber.

The flange b is preferably of considerable 95 length to permit the formation therein of front and rearward admission passages g and h for the passage of pressure fluid into bores j and k formed in the projections W and X and are divided by a wall V' in the valve V. 100

Pressure fluid for operating the drill may be conveyed from a suitable source of supply (not shown) to a connection o in the valve chest having a port p which opens into an annular supply passage q encircling the enlarged portion Q of the valve chamber. 105

In order to insure against cushioning of the valve V as it approaches its extreme positions, the plugs J and K are provided with suitable leak passages r which lead from the 110

ends of the enlarged portion Q to the atmosphere.

The operation of the device is as follows: With the valve in its extreme rearward position, illustrated in Figure 1, pressure fluid from the supply chamber q passes through the admission passage g, the bore j and through the inlet passage T into the rearward end of the cylinder to drive the piston C 10 forwardly. Shortly prior to the uncovering of the exhaust port B by the piston, said piston will overrun the kicker passage f whereupon a portion of pressure fluid passes into the rearward end of the enlarged portion Q 15 of the valve chamber and, acting against the actuating surface d will throw the valve V forwardly to the position illustrated in Figure 2.

However, while the piston C is travelling 20 forwardly and after it covers the exhaust port B the air in the front end of the cylinder A will be compressed and such compression flowing through the inlet passage U and the bore k will act against the wall V' of 25 the valve V to augment the live pressure fluid acting against the actuating surface d to throw the valve V forwardly.

With the valve in its forward extreme position, pressure fluid will flow through the 30 admission passage h, the bore k, thence through the inlet passage U to the front end of the cylinder to actuate the piston C rearwardly. As the piston C is travelling rearwardly, the kicker passage e will be uncovered thereby to admit pressure fluid into the 35 front end of the enlarged portion Q of the valve chamber for throwing the valve V to its initial position. During this stroke of the piston C the air in the rearward end of the cylinder A will of course also be compressed and such compression passing through the 40 inlet passage T and the bore j will act against the front surface of the wall V' and assist in throwing the valve rearwardly.

45 I claim:

1. In a fluid actuated rock drill, the combination of a cylinder and piston, a valve chest having a valve chamber and a supply chamber, inlet passages leading from the 50 valve chamber to the cylinder, a distributing valve in the valve chamber, said valve having bores in its ends and admission passages opening into the bores for admitting pressure fluid from the supply chamber into the 55 inlet passages, and kicker passages conveying pressure fluid from the cylinder to the valve chamber for actuating the valve.

2. In a fluid actuated rock drill, the combination of a cylinder and piston, a valve 60 chest having a valve chamber and a supply

chamber, inlet passages leading from the valve chamber to the cylinder, a distributing valve in the valve chamber having a central flange and reduced end projections, said projections having bores for conveying pressure 65 fluid to the inlet passages, admission passages in the flange affording communication between the supply chamber and the bores, and kicker passages in the valve chest conveying pressure fluid from the cylinder into 70 the valve chamber to act against the flange for actuating the valve.

3. In a fluid actuated rock drill, the combination of a cylinder and piston, a valve chest having a valve chamber and a supply 75 chamber, said valve chamber comprising an enlarged central portion and reduced end portions, inlet passages leading from the end portions to the cylinder, a distributing valve in the valve chamber having a central flange 80 and reduced end projections, said projections having bores for conveying pressure fluid to the inlet passages, admission passages in the flange affording communication between the supply chamber and the bores, said admission passages being movable into and out of registry with the supply chamber, and 85 kicker passages in the valve chest conveying pressure fluid from the cylinder into the enlarged portion of the valve chamber to act 90 against the valve for actuating said valve, said kicker passages being controlled by the piston.

4. In a fluid actuated rock drill, the combination of a cylinder and piston, a valve 95 chest having a valve chamber and a supply chamber, said valve chamber comprising an enlarged central portion and reduced end portions, crossed inlet passages leading from the end portions to the cylinder, a distributing valve in the valve chamber having end 100 projections with holding surfaces exposed intermittently to pressure fluid for holding the valve, said projections having bores for conveying pressure fluid to the inlet passages, a central flange on the valve having admission passages affording communication between the supply chamber and the bores, actuating surfaces on the ends of the flange, 105 kicker passages in the valve chest conveying pressure fluid from the cylinder into the enlarged portions of the valve chest to act against the actuating surface for actuating the valve, and leak passages in the valve chest 110 venting the ends of the enlarged portion of the valve chamber to the atmosphere.

In testimony whereof I have signed this specification.

EARL B. LEAR.
